UNITED STATES PATENT OFFICE

CHARLES MILLIRON, OF BARTLESVILLE, OKLAHOMA, ASSIGNOR OF ONE-HALF TO AMERICAN WELL & PROSPECTING COMPANY, OF CORSICANA, TEXAS, A CORPORATION OF TEXAS.

WELL-DRILLING APPARATUS.

No. 885,170.

Specification of Letters Patent.

Patented April 21, 1908.

Application filed November 23, 1906. Serial No. 344,768.

To all whom it may concern:

Be it known that I, CHARLES MILLIRON, a citizen of the United States, residing at Bartlesville, in the county of Cherokee, Oklahoma, have invented certain new and useful Improvements in Well-Drilling Apparatus; and I do hereby declare the following to be a full, clear, and exact description of the invention, such as will enable others skilled in the art to which it appertains to make and use the same.

This invention relates to improvements in a well drilling apparatus, and more particularly heads for oil well drills.

15 The invention comprises the production of a head that is formed with a casing, removable cover, and clamping means that are adapted to clamp various sized wires as may be desired.

20 The object in view is the production of a well drilling head that is easily and quickly secured in place and is quickly accommodated to various sized wires, and is adapted to firmly grasp the same.

25 Another object in view is the production of a casing head having a plurality of gripping members mounted therein, a removable cover for holding the gripping members in place, and means for adjusting the position 30 of the members for firmly grasping a wire that is adapted to pass therethrough.

With these and other objects in view the invention comprises certain novel constructions, combinations and arrangements of 35 parts as will be hereinafter more fully described and claimed.

In the accompanying drawings:—Figure 1 is a side elevation of my improved drill head and surrounding mechanism. Fig. 2 is a 40 vertical section through a drill head and surrounding mechanism. Fig. 3 is a vertical section through a drill head and surrounding mechanism at a right angle to the section upon which Fig. 1 is taken. Fig. 4 is a section taken on line A—B of Fig. 2.

In the digging and operating of wells, and particularly oil wells, it has been found desirable, under certain conditions, to operate the drilling mechanism while the liquid flows 50 from the well. Various means have been devised with more or less success for accomplishing this result. In these devices it has been customary in some instances to use a wire rope, and various clamping means have

been provided for holding the rope as the 55 same is operated. It is to this class of rope holding or gripping means that the present invention relates.

Referring more particularly to the drawings, 1 indicates the casing of a clamping head, and 2 a securing portion or nut shaped member that is adapted to have the casing 1 secured thereto and in turn be secured to a tube 3 that is adapted to reciprocate in a well. The tube 3 is adapted to reciprocate 65 in a cap 4 of any preferred construction which is adapted to direct oil or other liquid from the well casing 5 to any convenient point. The member 2 is provided with a hollowed-out portion 6 that is preferably threaded so 70 as to be easily attached to the tube 3. Above the hollowed-out portion 6 is another hollowed-out portion 7 which is connected to the hollowed-out portion 6 by a passageway 8 of a slightly larger size than the wire rope 75 or rod 9 that is adapted to be operated. The hollowed-out portion 7 is adapted to accommodate a projection 10 formed on the lower portion of the casing 1. The hollowed-out portion 7 and the extension or projection 10 80 are beveled in opposite directions for forming a stuffing box, as 11, containing packing 11' for preventing oil from passing up into the casing 1.

The casing 1 is made with a hollowed-out 85 portion 12 which is adapted to accommodate clamping members 13 and 14. A passageway 15 is provided between the hollowed-out portion 12 and the end of the extension 10 for accommodating the cable 9. The clamping members 13 and 14, as more clearly seen in Fig. 3, are made with their periphery of such a size as to snugly fit the hollowed-out portion 12 of the casing 1. When the outer surface or periphery of the members 13 and 14 are engaging the sides of the hollowed-out portion 12, the inner surface of the members 13 and 14 register with the opening 15, but the sides 13' and 14' of the members 13 and 14 do not meet. A tightening means, as set 95 100 screw 16, is positioned in the casing 1, and is adapted to force one of the clamping members as 14 over against the other member 13. When the member 14 is thus forced over against or toward the member 13, the cable 9 105 will be firmly grasped between the two clamping members 13 and 14 as clearly seen in the drawings. An adjusting and guiding mem-

ber 17 is positioned in the casing 1 and is adapted (to have its inner end fit into an elongated depression 17' for holding member 13 in correct position in relation to member 14. If desirable the member 17 may be forced inward so as to force the periphery of the member 13 out of contact with the walls of the hollowed-out portion 12. The member 13 may be forced out any desirable distance, and then the set screw 16 is operated for forcing the member 14 toward the member 13 for grasping the cable 9. In case, a very small cable is used, smaller clamping members 13 and 14 may be used and the members 16 and 17 will easily hold the same in position for firmly grasping the cable. A plate or covering 18 is firmly secured by suitable means as screws 19 to the casing 1. A suitable aperture 20 is provided in the plate 18 through which cable 9 is adapted to pass. The cover 18 is adapted to always firmly hold the clamping members 13 and 14 in position, so as to be always ready to grasp the rope or cable that may be passed through the casing 1. Secured in the member 2 in any convenient way as by threads 21 are members 22—22 which are adapted to pass through openings in the casing 1, and cover 18, and be secured in position by suitable means as nuts 23. The members 22—22 through the nuts 23 securely hold the casing 1 in contact with the member 2 and consequently firmly hold the extension 10 in position for compressing the packing 11' in the packing box 11. By this means the casing 1 is always held in position by the member 2 on the tube 3, and also the oil in the well is prevented from passing up the cable 9 into the casing 1 by the packing 11'. By providing a head with gripping means that are readily adjustable for various sized cables and for easily attaching and detaching as the occasion may require, a device is produced that is very desirable for use in digging oil wells, and especially wells that are flowing during the digging operation. The various means for adjusting the clamps for various cables is always of great advantage, as the same may be readily adapted for various occasions without any changing of the parts. By thus producing an article that will readily grasp a wire rope and the like, and one that may be readily attached and detached, a device is presented that is believed will present a structure that is very desirable when various stops and changes are necessary during the digging operation.

Having thus fully described my invention,

what I claim as new and desire to secure by Letters Patent is:—

1. A device of the character described comprising a casing formed with a hollowed out portion, clamping means conforming to the contour of the hollowed out portion of said casing positioned in said casing, and a plurality of set screws for operating said clamping means.

2. A drilling head comprising a casing, a plurality of loosely arranged clamping members formed with gripping faces positioned therein, and a plurality of set screws for adjusting and clamping said clamping means.

3. A drilling head comprising a casing, means for securing same in position, a pair of clamping members loosely mounted in said casing, means for adjusting the position of one of said clamping members and holding the same in its adjusted position, and a thumb screw for forcing the other of said clamping members toward the first mentioned clamping member.

4. A drilling head comprising a casing, means for securing the same in position, a plurality of clamping members mounted in said casing, one of said members being provided with an elongated depression, means passing through said casing and engaging said depression for guiding and adjusting said member, and means for forcing the other of said clamping members toward said member formed with said depression.

5. A drilling head comprising a casing, a plurality of clamping members loosely positioned in said casing, means for regulating the position of one of said members for grasping various size cables, and a set screw for forcing the other of said clamping members toward the one held in a set position.

6. A drilling head comprising a casing, loosely mounted clamping means positioned in said casing, means for varying the position of said clamping means, means for tightening said clamping means, a removable cover for said casing for holding said clamping means in the casing, means removably secured to said casing for securing the covering means in position, a packing for preventing liquid from entering said casing, and a packing box for holding in position said packing.

In testimony whereof I affix my signature in presence of two witnesses.

CHARLES MILLIRON.
